Primary Examiner—Prabhakar G. Deshmukh*Attorney, Agent, or Firm*—Phillip A. Rein**[57]****CLAIM**

The ornamental design for a horseticks game target assembly, as shown and described.

DESCRIPTION

FIG. 1 is a perspective view of the horseticks game target assembly of this invention;

FIG. 2 is an end elevational view thereof;

FIG. 3 is a top plan view thereof with a bottom plan view being identical;

FIG. 4 is a side elevational view with the opposite side elevational view being identical; and,

FIG. 5 is another end elevational view opposite that of FIG. 2.
